UNITED STATES PATENT OFFICE.

EDWARD ERICKSON, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

HEEL-LOADING MACHINE.

1,114,243.

Specification of Letters Patent.

Patented Oct. 20, 1914.

Application filed July 5, 1907, Serial No. 382,172.

Renewed November 7, 1913. Serial No. 799,813.

To all whom it may concern:

Be it known that I, EDWARD ERICKSON, of Boston, in the county of Suffolk and State of Massachusetts, have invented certain new and useful Improvements in Heel-Loading Machines, of which the following is a specification.

This invention has relation to heel-loading machines; that is, machines by which a plurality of nails or other fastenings are inserted in a heel preparatory to its attachment to a shoe.

The object of the invention is to expedite the operation of such machines so as to greatly increase the output thereof, and thus reduce the cost of manufacture of a shoe.

In the illustrated embodiment of the invention, this object is accomplished as follows: I provide a plurality of holders for the nails or other fastenings, which are moved successively into operative relation to heel blanks likewise successively fed into proper position. The nails, or other fastenings, are supplied from a suitable source through raceways to the nail-holders as they are successively moved into a nail-receiving position. The nail-holders are mounted upon a rotatable support or carrier which is advanced with a step-by-step motion so as to bring each holder, after it has been supplied with nails, into registration with a plurality of drivers mounted upon a driving head by which the nails are driven into a heel blank placed therebeneath. The heel blanks are presented successively to the nail-holders and the nail-driving mechanism by means of a carrier which is preferably arranged to rotate about an axis with a step-by-step movement. Arranged in proximity to the carrier, there is a punching mechanism comprising a head with a plurality of awls or punches for forming perforations in the heel blanks prior to the insertion of the nails, so that, in the operation of the machine, each heel is first perforated and then moved into position to receive the nails which are forced into it by the drivers, and then discharged from the carrier, by a suitable mechanism.

Referring to the accompanying drawings, Figure 1 represents a front elevation of a machine embodying the invention. Fig. 2 represents the side elevation of the same. Fig. 3 represents a horizontal section

through the machine on a plane above the carriers for the heels and the nail-holders. Fig. 4 is a fragmentary sectional view illustrating the raceways and the adjacent mechanism. Figs. 5 and 6 illustrate the picking device which cooperates with the ends of the raceways for simultaneously picking the required number of nails. Fig. 7 (Sheet 3) represents a section on the line 7—7 of Fig. 4. Fig. 8 represents an enlarged vertical section through the rotatable carriers for the heels and the nail-holders. Fig. 9 represents an enlarged section through the mechanism for feeding the nails to their carriers. Fig. 10 is a fragmentary view illustrating the ends of two raceways and the passageways leading therefrom to receive the nails as they are picked. Fig. 11 represents in plan view the carrier for the heels. Fig. 12 represents a sectional view through the carrier and its inclosing casing, together with the parts immediately therebeneath. Fig. 13 illustrates the device which controls the clamping of the heels.

Before describing the machine which I have illustrated as embodying the invention, I desire to have it understood that the invention may be embodied in various other forms of the machine and is not limited to the details of construction and arrangement which I have illustrated, nor to loading the heel blanks with the particular kind of fasteners shown and described; and that the phraseology which I have employed is for the purpose of description and not of limitation.

The machine is illustrated as having an upright main frame substantially rectangular in plan view. It has the base 20, the sides 21, 21, which are suitably connected by cross-braces and a horizontal top or table 22. Within the frame is arranged the most of the gearing and the power-transmitting mechanism. A cross-head 23, which in the present instance carries both the awls and the drivers, is secured to the upper ends of the parallel upright bars 24 which are mounted to slide in guides 25, 25 at the base of the machine, and in guides 26 near their upper ends as illustrated in Figs. 1, 2 and 3. The mechanism by which this cross-head is reciprocated, may be of any convenient form, such for instance, as that to be described. A main driving-shaft 27 is jour-

naled in the frame and has on its projecting end fast and loose pulleys 270, 28, with which may be engaged a driving belt. The said shaft 27 carries a gear 29 intermeshing 5 with and driving a gear 30 arranged on a shaft 31 journaled in the frame. Upon said shaft is affixed a disk 32 having a cam-groove 33. Secured to the two upright bars 24, 24, near their lower ends is a cross-bar 10 34 which is equipped with a roller 35 entering the cam-groove 33, so that, as the shaft 31 is rotated, the cam effects the reciproca-
tion of the cross-head 23.

Arranged above the table 22 are two rotary carriers 36 and 37, the former being for 15 the heel blanks and the other for the nail-holders, as illustrated in Fig. 3. The carrier 37 overlaps the carrier 36 (see Fig. 8), being arranged in a plane above it, so that a nail-holder may be positioned above a heel blank. The carrier 36 is mounted upon an upright shaft 38 journaled in the table 22. On the 20 lower end of the shaft 38 is a disk or wheel 39 which forms the driven member of a 25 Geneva stop-motion, the other member 40 of which (Fig. 3) is secured upon an upright shaft 41 journaled in the frame. The shaft 41 is equipped with a bevel gear 42 with which intermeshes a driving bevel gear 43 on the 30 shaft 31 hereinbefore referred to, as illustrated in Fig. 2. The member 40 is provided with an arm 44 carrying a roller 45 adapted to successively enter radial slots or grooves 46 in the disk or member 39, to impart a 35 step-by-step rotation to said member and consequently to the heel-blank carrier. The member 39 has its periphery concaved as at 47 to receive the convex portion or periphery of the member 40, and hold said member 40 at a state of rest after it has been fed one 40 step and until the roll 45 enters the next succeeding groove or slot therein. The Geneva stop-mechanism, or other power-transmitting mechanism which may be employed in lieu thereof, is so constructed that 45 the carrier for the heel blanks will be advanced one step, as through an arc of 90° for each complete rotation of the shaft 41; and as the bevel gears 42, 43, have the same 50 number of teeth, the cross-head is recipro- cated once for each advancement of the carrier. The parts are so timed that the carrier is advanced as the cross-head is completing its upward stroke and is descending 55 through the first portion of its downward stroke.

Secured upon the table 22 is a hood or casing 50. This is in the form of an inverted cup with an outstanding flange 51 which is 60 secured to the table by suitable fastenings. The casing is cut away at its rear portion so as not to overlap the carrier 37. It is provided with an aperture 52 at the front through which the heel blanks may be fed 65 to the carrier. Over this aperture may be

placed any suitable chute or feeding device for supplying heels automatically to the carriers. As shown, the heels may be supplied successively by hand, but I have contemplated utilizing any one of the various feeding mechanisms that have been heretofore suggested for successively feeding them. At 70 53 there is another aperture in the hood or casing to the right from that at 52 and at an angle of 90° therefrom. This aperture is 75 located over the point at which the heel blanks are discharged from the heel-carrier after the loading operation has been completed. To the left of the aperture 52 and at an angle of 90° therefrom, there is detachably set into the hood or casing a disk or 80 block 54 having a flange 55 (see Fig. 12) overlapping the upper surface of said hood. This block or disk is provided with a plurality of apertures 56 through which the 85 awls or punches may descend for the purpose of forming perforations or holes in the heel blank.

The carrier 36 is provided with four radial slots 57, as shown in Figs. 11 and 12. The end wall 158 of each slot serves as a guide and clamping member, against which the breast of the heel blank is forced by the complementary clamping member 58, of which one is placed in each of the slots. Each clamping member 58 is provided at its inner end with an upstanding pin 59 projecting upwardly through a radial slot 60 in a disk 61 placed upon the shaft 38. Each of the clamping members 58 is forced yielding- 90 outward by a spring 62 arranged in a socket in the inner end of the member and bearing against the inner end wall of the slot 57, as shown in Fig. 12. For the pur- 95 pose of controlling the movable clamping members 58 so that they will, at the proper times, engage and release the heel blanks, the hood 50 is centrally apertured to receive the upstanding ends of the pins 59 and also to receive a cam-guide 64 formed on a plate 100 65 suitably affixed upon the said hood, (see Figs. 12 and 13). The cam 64 is stationary, and, as the carrier 36 is advanced step-by- 105 step, each pin 59 engages said cam and is forced inwardly so as to release the heel 110 clamped by the member which carries the said pin, as the said member reaches its dis- 115 charging position. The cam 64 is long enough so that the clamping member 58 is held in its withdrawn position until the car- 120 rier is advanced one step, so that the heel blank may be fed into the carrier in position to be clamped. As soon as the carrier begins the next step, the pin rides off from the end of the cam and the spring 62 moves 125 the member forward so as to engage the rear of the heel blank and clamp it against the end 158 of the slot. To prevent the heel blank from dropping through the slot as it is fed thereto, there is arranged below the 130

carrier at the front of the machine a stationary support 66, as shown in dotted lines in Fig. 11, and in full lines in Fig. 8.

The carrier 37 for the nail-holders is formed with a hub 67, and it is loosely journaled upon an upright shaft 68 fixed in the table 22, as illustrated in Fig. 8. To said hub 67 there is attached a gear 69, which intermeshes with gear teeth formed on the periphery of the carrier 36. The ratio of the toothed carrier 36 to the gear 69 is as 2 to 1, so that as the carrier 36 is advanced through an arc of 90°, the carrier 37 is advanced through an arc of 180°. In case the carrier 37 has a greater number of nail-holders than is shown, the ratio will be correspondingly changed. The carrier 37 is formed with apertures to receive a plurality (in the present instance two) of the nail-holders 70. The apertures are circular and the nail-holders are cylindrical, being provided at their upper edges with peripheral flanges 71 so that they may be easily secured in place by suitable fastenings, as, for instance, screws 72. The nail-holders are arranged diametrically opposite from each other and are equi-distant from the axis of the rotation of the carrier. As the heel blank carrier is advanced one step, a nail-holder is brought into registration with a heel blank, so that the nails carried by the nail-holder may be driven into the heel blank and into the perforations or apertures previously formed therein, as illustrated in Figs. 3 and 8. Each nail-holder is provided with a plurality of apertures 73, properly spaced to receive the nails, each nail-holder in the present case being shown as provided with nine of said apertures. The nail-holders are removable and I provide for each machine a plurality of such holders for heels of different sizes. The nails are fed into the nail-holders successively, one nail-holder being filled with nails, while the other is in position to permit the nails therein to be driven into the heel blank. In order to prevent the nails from dropping through the apertures in the holders until the proper time, I form radial slots or guide-ways 74 in the under side of the carrier and place therein slides 75, each slide carrying a plate or gate 76, which is provided with perforations equal in number to and spaced correspondingly with the apertures in the nail-holder under which the plate lies. Each plate is removable from its slide so that it may be replaced by another one corresponding to the holder with which it is to be used. The slides and plates are movable from a position where the apertures in the plates register with the apertures in the nail-holders, to a position where the imperforate portions of the plate are beneath the apertures 73, and to accomplish this each slide 75 is provided with an

upstanding pin 175, on which there is a roller 77. These rollers extend into a cam groove 78 in a cam disk 79, rigidly affixed, as by a screw 80, to the upstanding shaft 68. The disk 79 is so placed and the cam groove 78 is so formed that just as a nail-holder moves into position to register with a heel blank on the heel blank carrier, the plate 76 beneath said holder is moved radially outward to cause these perforations to register with the perforations in the holder, and thus permit the nails to be discharged.

The cross-head 23, which I have previously described, is provided with two heads, which respectively carry a gang of awls and a gang of drivers. The head for the awls is indicated at 81 and that for the drivers at 82, the awls being indicated at 83 and the drivers at 84. The head 81 is dovetailed into an arm 85 which projects forwardly from the cross-head 23, so that the awls will be located above a heel blank after it has been fed one step by the carrier 36. The driver head 82 is dove-tailed into the cross-head 23 and it is located above the overlapping portions of the heel blank carrier 36 and the nail-holder carrier 37, so that the driver 84 will register with the apertures in each nail-holder as it reaches a position of registration with a heel blank on the heel-blank carrier. I provide for each machine a plurality of awl-carrying and nail-driving heads for heels of different sizes or shapes with the awls and drivers properly spaced for the purpose.

As thus far explained, it will be understood that each time the cross-head 23 is reciprocated, the heel-blank carrier is advanced one step through an arc of 90°, and the nail-holder carrier is advanced one step through an arc of 180°. As the cross-head moves downward, the awls form perforations in one heel blank and the drivers, entering the apertures in the loaded nail-holder, drive the nails therein into the apertures formed in the heel blank, which was previously perforated by the awl.

For the purpose of resisting the thrust of the awls upon the heel blanks, I place a jack under the awls and below the heel-blank carrier, as shown in Figs. 1 and 12. This jack is indicated at 87 and it is mounted upon the upstanding spindle 88, which is arranged to slide in a guide 89 formed in the table 22. The lower end of this spindle is pivoted to a lever 90 fulcrumed at 91 to one of the side walls of the frame. The said lever has a roll 92 placed in a cam groove 93 in a disk 94 rigidly secured upon a shaft 95 extending from front to rear of the machine and journaled in suitable cross-braces. The shaft is rotated by beveled gears 96, 97 (see Fig. 2), the former being secured to the shaft 41, and the latter to the shaft 95. The bevel gears have the same number of teeth 130

and are of the same size, so that the jack 87 is raised to engage and support the heel blank registering therewith, each time the cross-head is reciprocated, whereby the heel blank is supported against the downward thrust of the awls. It is also necessary to support the heel blank during the operation of driving the nails thereinto. Consequently I place below the driving head 82 and beneath the heel blank carrier a jack 141, as shown in Fig. 8. This jack, as well as that at 87, is shaped to conform to the curved face of the heel. It is secured upon a spindle or rod 142 which is adapted to slide in a bearing 143 formed on the table 22. The lower end of the spindle is provided with a roller 144 (see Fig. 2), which enters a cam-groove 145 in the cam disk 94 hereinbefore referred to. The cam groove is so shaped that the jack is raised to engage the heel immediately prior to the engagement of the drivers 84 with the nails so that the insertion of the nails in the heel blank may be properly accomplished. The operation of the two jacks 141 by the single cam disk insures their accurate co-operation with the awl and driver-head in pricking the heel blanks and driving the nails. After each heel blank is loaded and the clamping member is withdrawn, as previously described, it drops from the carrier upon a chute 98 which extends through the side of the hood 50, as shown in Fig. 1.

For the purpose of indexing the carrier 37 and thereby causing an accurate registration of the drivers with the apertures in the nail-holder, the carrier 37 is provided with two apertures 99 which are diametrically oppositely arranged as shown in Fig. 3, and the cross-head is provided with an indexing pin 100, the lower end of which is tapered so that as the cross-head descends, the pin will enter the forward aperture 99 and accurately locate or position the carrier 37. The pin may be made long enough, as shown, so as to pass through the aperture 99 into an aperture 101 in the heel-blank carrier and index that likewise, although I do not find this to be essential.

I will now describe the instrumentalities by which the nails are supplied to the nail-holders from one or more sources of supply. I provide a plurality of nail-hoppers, in the present case employing two, although more or less may be used. Each hopper has a rotary drum 102 mounted upon a shaft 103 journaled in a bracket 104, and an initial nail-receiving pot 111, with an inclined bottom 112, which discharges in the rotary portion 102 of the hopper. The drum of each hopper is provided with lifting buckets 105 for lifting the nails and discharging them into the raceways. The drums 102 are rotated from a transverse shaft 106 journaled in the sides of the main frame. On the outer ends of this shaft are belt wheels 107, from

which belts 108 extend to the drums, being placed in peripheral grooves therein. The shaft 106 is provided with a worm gear 109, with which intermeshes a worm 110 on the end of the shaft 95, hereinbefore described. 70

Between the pots 111 there is a plate 114, as illustrated in Fig. 4. This plate forms a support for the lower ends of the raceways, the picking mechanism and the guides for the nails. I employ as many raceways as there are apertures in each nail-holder. In the present instance, I have illustrated nine raceways, four extending from one hopper and five from the other hopper. These raceways are indicated at 115 and 116, those leading from one hopper being indicated by the former numeral and those leading from the other hopper being indicated by the latter numeral. The raceways in each set are placed side by side at an inclination both to the vertical and to the horizontal, and lead from the drum 102 through the pot downward to a block 117, which is superimposed upon a block 118 secured to the plate 114, by one or more screws 119, as shown in Fig. 9. 90 Each raceway consists of rabbeted bars 120, 120, secured together, as shown in Figs. 5 and 7, and a cover 121 separated far enough from the upper edges of the bars to permit the free passage of the nails down the raceway. The block 117 is provided with an aperture 122 at the end of each raceway, the aperture being of irregular form or key-hole shape, as shown. The nails *a* are illustrated as of the usual character employed for loading heels, (being known as collar nails), and have heads and collars or flanges immediately below their heads, though fastenings of other kinds may be employed. As each nail passes from the end of the raceway, it drops into the smaller end of the aperture 122 and its downward movement is arrested by the engagement of its collar with the surface of the block surrounding the smaller portion of the aperture. These apertures 122 are suitably spaced, being substantially in the same relation to each other as are the apertures in the nail-holder, and consequently some of the raceways are longer than others, as shown in Fig. 5. 115

A suitable picking mechanism is utilized to move the nails from the smaller portions of the apertures 122 to the larger portions thereof. For convenience, this picking mechanism consists of a single picker 123, which has at its edges notches 124 for the nails, adapted to register with the ends of the raceways and with the smaller portions of the apertures 122. The edges of the picker 123 adjacent the notches serve as stops to prevent the feeding of the nails through the raceway when the picker plate is advanced, as will be explained. The said picker is formed with an elongated slot 126 through which a guide 127 extends, said 130

guide being secured to the block 117 by a screw 128. The picker is reciprocated by the following devices, although other power-transmitting mechanism may be employed. 5 129 is an inverted L-shaped lever of which the lower end is fulcrumed upon a stud 130 carried by ears formed on a cross-bar 131. The ends of the cross-bar are affixed to the guides or bearings 26 on the table 22. The 10 lever 129 has at the junction of its two extremities a stud 132 which occupies a cam slot 133 formed in a plate 134 affixed to and movable with the cross-head 23. The upper extremity of the lever 129 is pivotally connected to the nail picker 123 by means of a link 135, and the cam slot 133 is of such shape that, as the cross-head moves downward, the picker 123 is moved rearward and the notches 124 therein carry the lowest 15 20 25 30 35 40 45 50 55 60 65 nails *a* in the raceways rearward to permit them to drop through the larger portions of the apertures 122; hence, each time the picker is moved rearward, the proper number of nails are simultaneously discharged from the raceways, and, through the means to be described, are delivered to the nail-holder which is in position to receive them. The block 118 is provided with apertures 136 registering with the larger portions of the apertures 122 to permit the passage of the nails therethrough. The blocks 117 and 118 could with convenience be made integral, though I have shown them as being formed separately for purposes of construction. The blocks are located directly above the rear part of the carrier for the nail-holders, so that as each nail-holder moves in a position to be supplied with nails, they may be delivered thereto. For the purposes 40 45 50 55 60 65 70 75 80 85 90 95 100 105 110 115 120 125 130 of guiding the nails from the blocks 117, 118 to the rearmost nail-holder 70, I provide a plurality of tubes 137, the upper ends of which extend into a block or plate 138, and the lower ends of each extend into a smaller block or plate 139, which is in a plane immediately above the upper surface of the carrier for the nail-holders. The blocks or plates 138, 139 are secured together by a screw 140. The plate 138 is dovetailed into the under side of the supporting plate 114, as shown in Fig. 4, and it is held against movement by a set-screw 141. The supporting plate 114 is apertured as at 144, to communicate with the passages through the tubes 137 and the blocks or plates 138, 139. The passages in the blocks 117, 118, 138, 139 and the tubes 137 all constitute conduits for leading or guiding the nails from the picking mechanism and the raceways to the nail-holders. I have shown the various parts last referred to as detachable, so that they may be replaced by others adapted for heel-blanks of other sizes. The arrangement and spacing 60 65 70 75 80 85 90 95 100 105 110 115 120 125 130 of the delivery ends of the raceways is pre-

cisely the same as that of the nail apertures in the nail holders. The nail conduits may therefore be straight and parallel to each other. Furthermore, the delivery ends of the raceways are so arranged with relation 70 to the conduits that the nails move all in the same direction when being transferred from the raceways to the conduits. The simplicity of the transferring device 123 is due to this arrangement of the raceways by 75 which the nails are all brought together from their several remote sources to the relative positions in which they go into the heel.

It is evident that other forms of guiding 80 means might be utilized than those I have described.

The operation of the machine need not be described in detail, as the operation of the various parts has been set forth in connection with their description. It is sufficient to state that for each reciprocation of the cross-head a heel blank is fed and perforated, a perforated blank is moved under the drivers, and a loaded blank is discharged from the heel-blank carrier. The picking mechanism is operated to permit the discharge of a proper number of nails to a nail-holder, the holder is carried to a position over the perforated heel blank, and 95 the nails are driven therefrom into the blank. Each heel blank is thus moved first to a position where the apertures are punched therein by the awls, thence to a position where it receives the nails from 100 the nail-holder, and thence to a position where it is discharged from the carrier through the chute 98 into a suitable receptacle provided for the purpose.

It will be observed that, while the awl head, the driver head, the awl guide, the nail holders and their gates, and the blocks and conduits for the nails are all detachable as previously described to be replaced by others particularly adapted for heel blanks of other sizes or shapes, the clamping members on the heel blank carriers are not necessarily detachable. I form these members at their ends with reentrant angles, or V-shaped recesses, as shown in Fig. 11, so that they will 115 engage and properly position heel blanks of different sizes and shapes. The carrier 86 itself may be easily removed from its shaft 38, and replaced by another carrier adapted for larger or smaller heel blanks as the case 120 may require. To secure the same elasticity of the machine with reference to the mechanism for delivering the nails to the holders, it will be seen that the raceways are not rigidly or unremovably attached; on the contrary the removable blocks 117 and 118 have lateral recesses 149 in which the ends of the raceways are frictionally inserted, and the raceways are laterally adjustable so that they may be operatively engaged with the 130

blocks used for other sizes or shapes of heels. In some cases, instead of adjusting the raceways and all the blocks, I have contemplated making only the blocks 138, 139 and the tubes removable, and replacing them by others in which the conduits therethrough will converge or diverge (as occasion may require) to deliver the nails into the nail holders.

10 Having thus explained the nature of my said invention and described a way of constructing and using the same, although without attempting to set forth all of the forms in which it may be made or all of the modes 15 of its use, what I claim is:—

1. In a heel loading machine, the combination of the following instrumentalities, to wit: a carrier, a plurality of nail holders, each having spaced nail apertures, means for 20 moving said carrier, and mechanism for feeding groups of nails successively to said holders, comprising a plurality of nail conduits terminating in proximity to said carrier, means for supplying nails to said conduits, and means for obstructing said nail-supplying means and for discharging a group of nails simultaneously therefrom into said conduits.

2. In a heel loading machine, the combination of the following instrumentalities, to 30 wit: a carrier, a nail driving mechanism, nail delivering means, a plurality of nail holders having spaced nail apertures on said carrier, means for feeding the carrier to cause each nail holder to move successively into registration with the nail delivering means and the nail driving mechanism, means for supplying nails to said nail delivering means, and means for intercepting the 40 nails in the nail-delivering means and effecting the discharge of a complete group thereof through said delivering means.

3. In a heel loading machine, the combination of the following instrumentalities, to 45 wit: a movable nail receiver for carrying a group of nails to the driving mechanism, inclined raceways for the nails, fixed means for receiving a group of nails from said raceways, said means having nail passages 50 through which the nails may gravitate, said fixed means coöperating with the lower ends of the raceways to support the nails by their heads in transit from the raceways to said nail passages, means for conducting the nails 55 from said fixed means to said movable receiver, and a reciprocating member adapted to move a group of nails from the raceways to said nail passages.

4. In a heel loading mechanism, the combination of the following instrumentalities, to 60 wit: a plurality of raceways having their ends spaced and arranged in a curved line similar to the curved edge of a heel, said raceways being arranged in two groups, 65 means for supplying said raceways with

nails comprising an elevator for each group, a picker coöperating with the ends of the raceways to pick groups of nails therefrom, and a holder having nail apertures arranged similarly to the ends of the raceways for receiving nails therefrom. 70

5. In a heel loading mechanism, the combination of the following instrumentalities, to wit: a plurality of raceways having their ends spaced and arranged in a curved line 75 similar to the curved edge of a heel, means for supplying said raceways with nails, a picker whose sides and end coöperate with the ends of the raceways to pick the nails therefrom, a holder having nail apertures 80 arranged similarly to the ends of the raceways for receiving nails therefrom, a nail driving mechanism, and operative connections between said picker and said nail driving mechanism. 85

6. In a heel loading mechanism, the combination of the following instrumentalities, to wit: oppositely arranged hoppers, a plurality of raceways arranged in groups of parallel raceways extending from said hoppers, means for feeding a plurality of nails to said raceways of each group, a block having apertures to receive the nails from the raceways, and a picker slide on said block adapted to engage groups of nails at the delivery ends of said raceways and directly deliver them to said block. 90

7. In a heel-loading mechanism, the combination of the following instrumentalities, to wit: oppositely arranged hoppers, a plurality of raceways extending from said hoppers, a block located between the delivery ends of said raceways and having apertures to receive nails from the raceways, a carrier, a nail holder mounted on said carrier, a sliding reciprocating picker on said block whose sides and end are adapted to engage groups of nails from said raceways and directly deliver them to said block, and nail driving mechanism. 100

8. In a heel loading machine, the combination of a rotary carrier having apertures therethrough to receive heel blanks, a head having a plurality of drivers, a jack in alignment with said head, means for moving said carrier step by step to bring said apertures into registration with said head and jack, mechanism for moving said head and jack toward and from each other, and spring tensioned means in each aperture for engaging the curved edge of the heel blank to position and hold it centrally in said aperture with the top and bottom of the blank exposed to the action of the jack and the drivers. 115

9. In a heel loading machine, the combination of a carrier rotatable in a fixed plane and having heel-blank-receiving apertures, yielding means for normally clamping heel blanks in said apertures, a head having a 120

plurality of awls, a head having a plurality of drivers, a jack in alinement with each head, means for moving said carrier to bring each aperture therein into registration with said heads and their alined jacks successively, and means for moving the said heads and their alined jacks toward and from each other.

10. In a heel loading mechanism, the combination of the following instrumentalities, to wit: a rotatory carrier held against axial movement, having a plurality of spaced apertures with clamps for the heel blanks, and means for operating said clamps to clamp the blanks in and release them from said apertures, means for operating upon said blanks successively, and a movable jack or abutment movable toward and from said carrier for engaging said blanks successively 15 to resist the thrust of said means thereon and prevent the dislodgment of the blanks from said clamps and apertures.

11. In a heel loading mechanism, the combination of the following instrumentalities, to wit: a rotatory carrier, having a plurality of spaced apertures with clamps therein for engaging the edges of the heel blanks, and means for operating said clamps to clamp and release the blanks, in combination with 20 a movable nail holder, and nail driving mechanism, and a jack to support the heel blanks in the nailing operation.

12. In a heel loading mechanism, the combination of the following instrumentalities, to wit: a rotatory carrier having apertures with clamps therein for the reception of a plurality of heel blanks, a hood or casing having an aperture for the feeding of blanks to said carrier, and stationary means below 35 said carrier to position said blanks in said apertures and clamps.

13. In a heel loading mechanism, the combination of the following instrumentalities, to wit: a rotatable carrier having apertures and clamps therein for the reception of a plurality of heel blanks, a casing having an aperture for the feeding of heel blanks to said carrier, a head having a plurality of awls, means for reciprocating said head, a 40 jack below said head movable toward and from the carrier to engage the blanks successively, and means for actuating said jack.

14. In a heel loading mechanism, the combination of the following instrumentalities, to wit: a rotatable carrier held against axial movement and having a plurality of slots, clamping members in said slots, spring-tensioned means for normally closing said clamping members, a fixed cam for opening 55 said clamping members, and coöperating jacking means, and heel treating means movable relatively to the carrier.

15. In a heel loading mechanism, the combination of the following instrumentalities, to wit: a rotatable carrier having a plural-

ity of clamping members for engaging and clamping heel blanks, means for causing the opening and closing of said clamping members, and a support below and independent of the carrier for engaging and supporting 60 the heel blanks prior to their engagement by said clamping members.

16. In a heel loading mechanism, the combination of the following instrumentalities to wit: a rotatable carrier having a plurality of apertures therethrough with clamping members therein for engaging and clamping the heel blanks, means for perforating the heel blanks, means for driving nails into the perforated heel blanks, vertically reciprocatory jacks in alinement with said perforating and nail-driving means, means for rotating the carrier with a step by step movement relatively to said jacks and said perforating and nail driving means, yielding means for normally closing said clamps, and means for opening said clamps to discharge the loaded heels and receive heel blanks to be operated on.

17. In a heel loading mechanism, the combination of the following instrumentalities, to wit: a nail driving mechanism, a rotatable carrier, means for actuating said carrier, a plurality of nail holders thereon, a gate coöperating with each nail holder, a 95 slide for each gate, and a cam for operating said slides.

18. In a heel loading machine the combination of the following instrumentalities, to wit: a nail holder having spaced nail apertures, a carrier therefor, a plurality of raceways, means for depositing nails in the raceways, means for intercepting the nails in the raceways and for releasing them in successive groups, and straight conduits for 100 conducting the nails from said releasing means to the apertures in said holder.

19. In a heel loading machine the combination of the following instrumentalities, to wit: a nail holder having spaced nail apertures, a carrier therefor, straight parallel conduits for conducting nails to said apertures, and means for depositing a group of nails one into each of said conduits.

20. A heel loading machine comprising a movable head having a plurality of nail drivers, a nail holder having nail receiving apertures spaced the same as said drivers, means for delivering nails to said holder, a carrier for moving said nail holder from 115 nail receiving position to operative relation with said drivers, said nail holder being affixed to said carrier, a plate movably mounted on said carrier below said nail holder, said plate being adapted to cover 120 said apertures, and having apertures arranged to register with the apertures of said holder when the plate is moved to one position, a fixed member, and connections between said plate and said fixed member 125 130.

whereby said plate is moved to said position when said nail holder is placed in operative relation to said drivers.

21. A heel loading machine comprising a nail holder having spaced nail receiving apertures, nail raceways for supplying nails to said nail apertures, the delivery ends of said raceways being arranged and spaced the same as the arrangement and spacing of said apertures, conduits for conducting nails from said raceways to said apertures, and means for effecting the discharge of nails in groups from said raceways to said conduits.

15 22. A heel loading machine comprising a nail holder having nail receiving apertures, conduits for conducting nails to said apertures, nail raceways for supplying nails to said conduits, the delivery ends of said raceways being offset with relation to said conduits and arranged so as to support flanged nails by their flanges while the nails move across the ends of the raceways to said conduits, and means for moving the nails across 25 the ends of the raceways to said conduits while the nails are supported by the raceways.

23. A heel building machine comprising a holder having nail receiving apertures, conduits for conducting nails to said apertures, nail raceways for supplying nails to the several conduits, and a member having a rectilinear movement for transferring nails simultaneously from the several raceways to the several conduits.

24. A heel loading machine comprising a holder having nail receiving apertures, conduits for conducting nails to said apertures, nail raceways for delivering nails to said conduits, the delivery ends of said raceways being arranged so that the nails from them all move in the same direction transversely of the raceways in moving from the raceways to said conduits, and means for moving 45 the nails from said raceways to said conduits.

25. A rotatable carrier having a plurality of heel-blank-receiving apertures, clamping members in said apertures for clamping the

heel blanks against the carrier, yielding 50 means for normally closing said clamps, means for piercing the heel blanks in said apertures, stationary means for supporting a heel blank in position to be clamped by said clamping members, means for rotating 55 said carrier step by step to cause said apertures to register successively with said heel-blank-supporting means, and means for opening said clamping members successively as they approach said supporting means and 60 for holding them open until after they start to move away from said supporting means.

26. In a heel loading machine, the combination of the following instrumentalities, to wit: a movable nail receiver for carrying a 65 group of nails to the driving mechanism, inclined raceways for the nails, fixed means for receiving a group of nails from said raceways, said means having nail passages through which the nails may gravitate, said 70 fixed means and the lower ends of the raceways co-operating to guide the nails laterally from the raceways to said passages and to support the nails by their heads in transit to said passages, and a reciprocatory member adapted to move a group of nails from the raceways to said passages.

27. In a heel loading machine, the combination of the following instrumentalities, to wit: a movable nail receiver for carrying a 80 group of nails to the driving mechanism, inclined raceways adapted to support the nails by the under sides of their heads, fixed means for receiving a group of nails from said raceways, said means having passages 85 out of line with the raceways through which passages the nails may drop, and a reciprocatory member adapted to transfer a group of nails from the raceways to said passages by engaging the edges of the nail heads and 90 thereby pushing the nails transversely upon the lower ends of the raceways.

In testimony whereof I have affixed my signature, in presence of two witnesses.

EDWARD ERICKSON.
